UNITED STATES PATENT OFFICE

2,128,805

SUPPORT FOR ELASTIC FLUID TURBINES

John H. Doran, Scotia, N. Y., assignor to General
Electric Company, a corporation of New York

Application September 11, 1937, Serial No. 163,504

5 Claims. (Cl. 253—39)

Elastic fluid turbines in order to withstand the high pressures to which they are subjected have relatively massive casings. On account of the high temperature of the operating fluid, movements of the casing both axially and radially take place due to expansion and contraction from cold to hot and vice versa. Such movements are usually greater in an axial than in a radial direction. The effects of temperature changes are particularly noticeable at the inlet or high pressure end of the turbine, the low pressure end being anchored. Because such movements cannot be prevented, it becomes important to provide means for supporting the casing in such manner that as said movements are taking place and after they are completed, proper alignment of the parts is preserved.

The object of my invention is the provision of an improved means or arrangement of parts which permits the casing of an elastic fluid turbine freely to expand and contract both axially and radially and at the same time preserves the proper alignment of the co-operating parts and prevents distortion of the casing.

For a consideration of what I believe to be novel and my invention, attention is directed to the accompanying specification and the claims appended thereto.

In the attached drawing, which is illustrative of my invention, Fig. 1 is a perspective end view of a turbine and its support; Fig. 2 is a view in elevation of a slightly modified form of support, and Fig. 3 is a detail showing how the lever arms of the supporting members are connected.

In the drawing, 3 indicates the high pressure end of the casing of an elastic fluid turbine, the parts of which may be of any suitable construction. Extending forwardly from the high pressure end of the casing and parallel to the axis of the shaft of the turbine rotor are two relatively massive arms or extensions 4 and 5 which support the front end of said casing and of the parts contained therein. The rear or low pressure end of the casing may be supported in any suitable or known way. The temperature of the low pressure or exhaust end of a turbine when operating condensing, as most large turbines do, is relatively low, and does not change greatly with changes in load, and for that reason it is entirely practical to firmly anchor the exhaust or cold end and take care of expansive movements at the inlet or hot end as in the present case. Under the arms 4 and 5 are located supporting members 6 and 7 each of which forms a bell crank lever. The part of each member directly under

a supporting arm is of I-beam formation having a relatively thin web 8 extending at right angles to a plane passing vertically through the axis of the turbine. Each member is rigid in a vertical plane so as to support the weight of the turbine without flexing. The upper end of the web has an enlarged integral head 9 forming a seat for a supporting arm of the casing, said seat and arm being united by suitable means, as for example bolts 10. The bottom end of the web is provided with an enlarged integral foot 11, the web gradually increasing in width in a transverse plane from the head to the foot. The form or shape of each member is such that the web will bend or yield by the necessary amount when the turbine casing expands and contracts in the direction of its axis but is rigid against sidewise movements so that the axial alignment of the turbine is preserved.

The radial expansion and contraction of the turbine casing while appreciably less than the axial expansion and contraction thereof nevertheless has to be taken care of. To this end, the base, bed plate or support 12 has what in effect constitutes a knife edge pivot or fulcrum 13 for each member. Because the weight of the turbine would tend to crush a true knife edge, the pivot is rounded at upper end so as to give a greater area of support. A pivot or fulcrum is located in a seat 14 formed in the foot 11 of each member and extends in the same direction as the axis of the casing. Such a construction permits the members to tilt by the very small but necessary amount when the casing expands and contracts radially. The arrangement of the pivots 13 and seats 14 also permit the members as a whole, where necessary or desirable, to slide back and forth as the casing expands and contracts but in many cases the vertical webs 8 will bend sufficiently for the purpose. To ensure equal movements of the members, as distinguished from permitting one to do all or a greater part of the tilting and thus cause objectionable disalignment of the front end of the turbine casing with respect to the rear or low pressure end, the two members are pivotally connected. This is accomplished by providing each member with a lever arm 15 and connecting the two arms by a pivot 16.

Referring to Fig. 2, the same general construction as that referred to above is followed but with the following differences. Instead of having the relatively large flat surfaces of the casing arms 5 rest directly on the heads 9 of the members, there are interposed metal supporting

50

55

strips 17 of substantially smaller surface area. Because the supporting strips are narrower than the arms, they in effect form fulcra and permit of a limited tilting of the members.

5 Instead of using knife edge supports 13 and seats 14 therefore, as in Fig. 1, narrow supporting strips 18 are substituted therefor and holding down bolts 19 provided, the latter being secured in the bed plate 12. The narrow supports in 10 effect form fulcra and permit of the necessary tilting movement of the members to compensate for radial expansion of the casing. The axial expansion of the casing may be taken care of by the bending of the webs 8 or the bolts 19 15 may be so adjusted and arranged as to permit movement of the members on the base or bed plate 12 or a combination of both features may be employed.

In Fig. 3 is shown a suitable arrangement for 20 connecting the lever arms 15 of the supporting members and is equally applicable to the structures of Figs. 1 and 2. On opposite sides of one of the arms is secured a pair of plates 20 by bolts 21 and desirably in addition by a welded joint 22. 25 The other arm is made to fit between the plates and the parts so fitted are united by a pivot pin 23 having suitable means at its ends to hold it in place.

Since the internal mechanism of the turbine 30 forms no part of the present invention, it has been omitted but it is to be understood that it can be of any suitable type. The front end bearing for the rotor is mounted in the forwardly extending part 24 of the casing so that the entire mass at 35 the front end is supported by the members 8 and 7.

It must be understood that the movements of 40 the casing due to heat changes are small, so small in fact that usually it is only by accurate measurements that the extent thereof can be determined. Since expansive movements of the casing due to 45 temperature changes cannot be prevented, the only thing that can be done is to provide supporting, guiding and directing means capable of preserving the proper predetermined alignment of the casing and its parts with respect to some fixed point. The means described above permit the desired results to be secured.

What I claim as new and desire to secure by 50 Letters Patent of the United States, is:

1. An elastic fluid turbine having a casing, parts 55 of which move both axially and radially in response to temperature changes, a base, a pair of members extending transversely to the axis of the casing and secured thereto for supporting a part of the weight thereof and preserving the axial alignment of the casing as it expands and contracts in the direction of its length, said members being yieldable in an axial direction and rigid

in a plane perpendicular thereto, fulcrum supports for the members carried by the base permitting the members to tilt as the casing expands and contracts radially, and means connecting the members in a manner to cause equal tilting movements thereof. 5

2. An elastic fluid turbine having a casing, parts of which move both axially and radially in response to temperature changes, a base, extensions on the casing at the hot end thereof on opposite 10 sides of its axis, a supporting member located under each extension and secured thereto for sustaining a part of the weight of the casing and preserving its alignment as it expands and contracts in an axial direction, and means located 15 between the base and the members permitting the latter to tilt in response to radial expansions of the casing.

3. An elastic fluid turbine having a casing, parts of which move both axially and radially in 20 response to temperature changes of the operating fluid, extensions on the casing located on opposite sides of its axis, a supporting member under each extension and secured thereto, said members being rigid in a vertical plane and movable in the direction of the axis of the casing and also in a plane transverse thereto, means connecting the members so that movements thereof due to radial expansion of the casing are equalized, and a base 25 common to and supporting said members. 30

4. An elastic fluid turbine having a casing, parts of which move both axially and radially in response to temperature changes of the operating fluid, a base, extensions secured to the casing at the hot end thereof and located on opposite sides 35 of its axis, a pair of members fulcrumed on the base and engaging the extensions to support the weight of the casing, each of said members forming a bell crank lever, and means uniting corresponding lever arms of said members in a manner to equalize their movements in a direction 40 perpendicular to the axis of the casing.

5. An elastic fluid turbine having a casing, parts of which move both axially and radially in response to temperature changes of the operating 45 fluid, a base, a pair of members supported on the base, each having a head engaging the casing, a foot and a web connecting the head and foot, said web extending transversely to the axis of the casing and being rigid in a vertical plane and yieldable in an axial direction, and fulcra for the members supported by the base and extending parallel to each other and to the axis of the casing and co-operating with said feet, said members tilting toward and away from each other as the casing expands and contracts radially under temperature changes. 50

JOHN H. DORAN.
